UNITED STATES PATENT OFFICE.

JAMES EDISON ERSKINE, OF JACKSONVILLE, FLORIDA.

MONOGRAM.

Application filed December 29, 1924. Serial No. 758,662.

This invention relates to an improvement in monograms, especially designed and adapted for use on automobiles although, of course, capable of other applications and 5 uses.

An object of the invention is to provide a monogram which may be made up of several separate letters corresponding to the initials of the name forming the subject-matter of 10 the monogram, the letters being capable of ready and easy association to constitute an apparently unitary and solid monogram whereby the letters may be provided in quantity at a comparatively slight expense 15 and monograms may be made up as desired without the exercise of special skill or without the use of special tools.

A further object is the provision of a monogram of this character which is of highly attractive appearance and which is comparatively easy and inexpensive to produce 20 and assemble.

Other objects and advantages reside in certain novel features of the construction, 25 arrangement and combination of parts which will be hereinafter more fully described and particularly pointed out in the appended claim, reference being had to the accompanying drawings forming a part of this specification, and in which:

Figure 1 is a view in front elevation of a monogram constructed in accordance with the present invention,

Figure 2 is a view in section on the line 35 2—2 of Figure 1,

Figure 3 is a group view in perspective showing the parts of the monogram prior to assembly,

Figure 4 is a sectional view of the center 40 letter taken in the plane of line 4—4 of Fig. 1, and

Figure 5 is a detail view in elevation showing a "center" formed with a different letter from that shown in Figures 1 and 3.

Referring to the drawings, the numeral 5 designates generally a carrier which consists of a flat base plate 7 of circular form and having an inwardly directed bead 8 around its periphery. The base plate 7 is provided 45 with a countersunk opening 9 at its center which receives the beveled head of an attaching bolt 10 designed to extend through the structure to which the monogram is to be attached. The bolt is held in position by means of a nut 11 and spring washers 12.

Of course, it is to be understood that any suitable type of attaching means may be employed.

The base plate 7 is enlarged adjacent its periphery to provide a rim 13, the outer 60 surface of which may be suitably ornamented. The rim 13 is machined to provide an outwardly directed annular flange 14 having an inwardly curved lip 15 extending around its outer edge. 65

Letters corresponding to the initials of the name which forms the subject-matter of the monogram are placed in the cavity or recess defined on the carrier by the flange 14 and its lip 15. As the flange 14 and its 70 lip 15 are of annular form the cavity is of cylindrical form or circular in cross section. The letters may be constructed of brass or any other suitable material. The letters are provided in "rights" 16, "lefts" 17 and "centers" 18 corresponding to the initials of the 75 surname, Christian name and middle name, respectively. The "rights" and "lefts" which correspond to the surname and Christian name have the form of a segment of a circle 80 and the "centers" which correspond to the middle name, or which may be blanks when no middle initial is desired, are in the form of section of a circle defined by two chords parallel to a diameter and to each other and 85 the arcs intercepted by the chords. It is to be understood that if desirable the "rights" and "lefts" may be in the form of semi-circles and the "centers" corresponding to the middle initial may be omitted when no middle 90 initial is employed in the monogram. Each letter includes a prismatic background 19 made up of striations 19^a of triangular form in cross section and having their exposed faces constituting light-reflecting surfaces. 95

With this form of background the line of juncture between the separate letters of the assembly is concealed and the letters appear to be formed on a single background. The letters proper are designated at 20 and are provided in relief on their respective backgrounds. Periods 21 may also be provided in relief on the backgrounds of the letters. The several separate letters which are used to make up the monogram, when assembled, have the form of a disc designed to snugly fit in the recess or cavity defined by the flange 14 and lip 15. The letters when assembled are provided around their periphery with a continuous beveled shoulder 22, each letter

- having a portion of such shoulder formed on its periphery and the several portions of the shoulder being complementary to provide the complete shoulder in the assembly.
- 5 The shoulder 22 thus formed around the periphery of the assembled letters is adjacent to or slightly inwardly of the lip 15 and in the space between the shoulder 22 and the lip 15 a resilient retaining ring 23 is snapped to hold the letters assembled. With this arrangement a dealer in monograms may be provided with "rights", "lefts" and "centers" of each letter and a suitable number of bases, retaining rings 15 and attaching devices so that a monogram made up of any combination of letters may be readily provided without the necessity of the exercise of any special skill or special tools.
- 10 20 The periods provided in the monogram are

preferably formed on the center letter, as indicated at 21^a in Figure 5.

It is to be understood that the monograms may be made up of standardized "rights", "lefts", and "centers" of various shapes and 25 these "rights", "lefts" and "centers" may be complementary sections of ovals, diamonds, rectangles, or other shapes of figures, the complete monogram conforming, of course, to the outline of the back employed. 30

I claim:

In a monogram, separate letters designed to be assembled to give the appearance of a complete and unitary monogram, each letter having a background made up of triangular 35 striations, the faces of which provide light reflecting surfaces whereby the line of junction between the letters is concealed.

JAMES EDISON ERSKINE.
